VENETIAN BLIND

Charles H. Wood, Oakland, Calif.

Application March 21, 1938, Serial No. 197,166

3 Claims. (Cl. 156—17)

This invention relates to the type of closure for windows and the like commonly referred to as Venetian blinds.

It is an object of my invention to provide a simplified structure of the class described.

Another object of my invention is to provide, in a Venetian blind structure, unitary means for raising the blind to clear the window, or other opening over which it is mounted, or for tilting the slats of the blind to various angular positions so as to cover the opening to various degrees.

A further object of the invention is to provide a structure composed of a greatly lessened number of parts than is found in the conventional Venetian blind thereby rendering the blind of my invention capable of being manufactured and sold at a materially lower cost than the conventional blind.

The invention possesses other objects and features of advantage, some of which, together with the foregoing, will be specifically set forth in the detailed description of the invention hereunto annexed. It is to be understood that the invention is not to be limited to the particular form thereof herein shown and described as various other embodiments thereof may be employed within the scope of the appended claims.

Referring to the drawings:

Figure 1 is a front elevational view of a complete Venetian blind embodying the improvements of my invention. Portions of the view are omitted so as to conserve space in the drawings.

Figure 2 is a vertical sectional view of the structure shown in Figure 1 showing the slats in their fully opened position. The plane in which the view is taken is indicated by the line 2—2 of Figure 1.

Figure 3 is a view similar to Figure 2 showing the slats in a tilted position.

Figure 4 is a view similar to Figures 2 and 3 showing the blind raised to uncover a portion of the opening in which it is hung.

In detail, I have shown, for purposes of illustration, a rectangular frame composed of a pair of vertically disposed stiles 6 joined together at their upper ends by a top rail 7 and at their lower ends by a bottom rail 8. Within the opening defined by the frame, and secured to the top rail 7 by suitable means such as the wood screws 9, is a header bar 11 provided with a longitudinally extending groove which forms a hollow chamber 12 within the bar.

Secured to each of the stiles 6, by suitable screws 13, directly below the header bar, is a pair of brackets 14 each being provided, as is best

shown in Figure 1, with an offset portion 16 apertured to receive and rotatably journal pivot pins 17 which are secured in and protrude from the ends of a tilt bar 18. The pins 17 are located centrally of the ends of the bar 18 and on the longitudinal axis thereof so that the bar is mounted for rotary motion about the said axis. Attached to and depending, in spaced relation, from opposite edges of the tilt bar 18 are spaced pairs of fabric support straps 19, each pair of which is provided, at spaced intervals longitudinally thereof, with horizontally disposed fabric stirrups 21 which are attached to or integrally interwoven with the support straps 19. These stirrups engage and support a plurality of thin slats or shutter blades 22, the slats being spaced apart equal to the spacing of the stirrups. The lower ends of the support straps 19 pass over opposite edges of a lower tilt bar 23 and are secured, in any suitable manner, to the lower side of the latter bar. The lower tilt bar, like the upper bar 18, is provided at its ends with pivot pins 24 which are secured in and protrude from the bar and are releasably engageable with brackets 26, one of which is best shown in Figure 4, having an offset portion 27 provided with a reversed L-shaped notch 28. The length of the straps 19 is such that when the blind is in its lowered position, as shown in Figure 1, each pivot pin 24 will be positioned slightly above the opening of a notch 28 so that in order to insert the pins into the notches downward pressure must be imposed on the lower tilt bar 23. This will stretch the straps 19 whereupon the pins may be pushed into the notches and upon release of the pressure on the tilt bar the pins will be pulled upwardly into the seat 29 wherein they will be forcibly held by the tensioned straps 19 against accidental displacement. Thus, both the upper and lower tilt bars, and the slats 22, are mounted for rotational movement simultaneously about their respective longitudinal axes since they are each connected together at their edges by the support straps 19.

Means are provided for rotating the upper tilt bar so as to move the slats into various tilted positions and the said means also function to permit upward collapsing of the blind so as to uncover various portions of the frame opening. Positioned adjacent one side of the opening is a doubled cord 31, the loop 32 thereof being sufficiently extended downwardly as to be within easy reach of a person standing in front of or below the opening. This doubled cord passes upwardly through an aperture 33 formed adjacent one end of the header bar 11, over a guide sheave 34

34 and horizontally along the hollow chamber 12. One cord 36 of the pair is trained over a tilted guide pulley 37, mounted within the chamber 12 in a centralized position over the right hand set 5 of support straps 19, and passes downwardly out of the header bar and toward the rear edge of the tilt bar 18 as viewed in Figure 1, through an inclined aperture 38 formed in the bottom of the header bar. The other cord 39 of the pair extends 10 along the chamber 12 and is trained over a guide pulley 41, centrally located over the left hand set of support straps 19 and tilted oppositely to the pulley 37, and passes downwardly and out of the header bar toward the front edge of the tilt bar 15 through an aperture 42 inclined oppositely to the aperture 38.

Formed in the tilt bar 18 centrally over the support straps 19 is a pair of notches 43 and 44 the former of which, positioned over the right-hand pair of support straps 19, opens at the rear edge of the tilt bar, as viewed in Figure 1, and the latter of which, positioned centrally over the left-hand pair of support straps, opens at the front edge of the tilt bar. Journalized in brackets 20 46, attached in any suitable manner to the bottom surface of the tilt bar and extending into the notches 43 and 44, are pairs of rotatable guide pulleys 47, the pulleys being so arranged, as is best shown in Figures 2 to 4 inclusive, that 25 one pulley of each pair is positioned preferably tangential with the longitudinal center line of the tilt bar while the other pulley of each pair is disposed in horizontally spaced relation with the first mentioned pulleys and adjacent the longitudinal edges of the tilt bar. The spacing of the 30 outermost pulley 47 of each pair thereof from the rotational axis of the tilt bar provides, as will hereinafter appear, a pair of opposed cranks by means of which the tilt bar may be rotated, selectively, in either direction.

The cord 36, after passing downwardly through the aperture 38, is trained over and under the outermost pulley 47 of the right-hand pair, as shown in Figure 2, then upwardly between the 45 pulleys and over the innermost pulley of the pair and then directly downwardly through the elongated apertures 48 formed in each of the slats 22, medially of the width of the support straps 19, and through a suitable aperture 49 formed 50 in the lower tilt bar 23. After passing through the aperture 49 the cord is provided with a knot 51 which reposes in a counterbored portion 52 of the aperture 49 so as to secure the cord and tilt bar together. The other cord 39, after passing 55 downwardly through the aperture 42, is trained over and under the outermost pulley 47 of the left-hand pair, then upwardly between the pulleys and over the innermost pulley of the pair and then downwardly through additional apertures 48 formed in each of the slats 22 medially 60 of the width of the left-hand pair of support straps 19. The lower end of the cord 39 is secured by a knot 53 in the counterbore 54, provided in the lower tilt bar 23, which forms part 65 of the aperture 56, the latter being equivalent to the aperture 49 described above. In order to clear the cords 36 and 39, as the lower tilt bar is oscillated back and forth, the latter is cut away to provide V-shaped grooves 57 in which the 70 cords may move as is most clearly shown in Figure 3. The provision of these grooves insures that at all times during tilting of the blind the cords will be maintained substantially in alignment with the axes of rotation of the several 75 rotatable blind elements.

It will be seen, in Figures 2 and 3, that when the pivot pins 24 of the lower tilt bar 23 are engaged with the brackets 26 and one of the cords 31 forming the loop 32, which in this case is the left-hand cord shown in Figure 1, is pulled downwardly while the other cord of the loop remains free, the tension in the cord will tend to straighten out the S-shaped bend where the cord passes over the pulleys 47 with the result that the outermost pulley will be forced upwardly thereby forcing the upper tilt bar to rotate about its longitudinal axis. This movement of the upper tilt bar will result, as is shown in Figure 3, in the slats 22 and the lower tilt bar moving simultaneously and equally with the upper tilt bar onto any inclined position, depending upon the degree of pull imposed on the cord, between horizontal and the maximum position indicated in the last-named figure of the drawings. Similarly, a downward pull on the right-hand cord 20 31 shown in Figure 1 will move the tilted blind elements to any position between that shown in Figure 3 to a maximum tilted position reversed from that shown in the latter figure. In order to limit the degree of tilt of the upper tilt bar, the latter is provided at one end with a pair of spaced stop pins 58 which, as the bar 18 moves, strike alternately against the sides of the bracket 14 thereby prohibiting movement of the tilt bar beyond the inclined position in which it is shown 25 in Figure 3.

The blind may be collapsed upwardly so as to uncover a large or a lesser portion of the frame opening. It will be seen that if the lower tilt bar is freed from the brackets 26, and both pull cords 31 are drawn downwardly equally and simultaneously, the cords 36 and 39 will be tensioned to move the tilt bar 23 upwardly and, as it contacts successive of the slats 22 during its movement, will also elevate the slats until all of the latter 40 have been moved upwardly to positions below the upper tilt bar 18 as is clearly shown in Figure 4. In order to hold the collapsed blind in the position shown in the latter figure, I provide a latch for the pull cords which prevents their retraction. 45 This latch preferably takes the form of an arm 59 which is pivotally mounted on a pin 61 secured in the bracket in which the sheave 34 is journaled, having an arcuate surface 62 thereon whose radius progressively increases from a minimum, which is less than the distance from the axis of the pin 61 to the confronting surface of the cord where it passes over the sheave, to a maximum, which is greater than the aforesaid radial distance. Thus, when it is desired to retain the pull cords in a given position after they 50 have been drawn downwardly, the operator moves the cords at arm's length to his right, as viewed in Figure 1, until the cords contact the curved surface 62 of the latch arm. Then, holding the 55 cords in the above-mentioned extended position and allowing them to retract a slight amount, the arm 59 will be moved upwardly until, at a point on its curved periphery, the cords will be clamped between the said periphery and the sheave 34. 60 The above locking operation may also be performed when it is desired to latch the blind in any tilted position.

Having thus described my invention and its mode of operation, what I claim is:

1. A device of the class described comprising a frame bordering an opening, an upper tilt bar pivotally mounted for rotational movement about its longitudinal axis on said frame adjacent one side of said opening, a lower tilt bar likewise 70

- pivotedly mounted on said frame adjacent the opposite side of said opening, a plurality of shutter blades positioned in said opening between said tilt bars, means connecting said tilt bars and said shutter blades together for supporting said shutter blades in spaced relation to each other and to said tilt bars and whereby upon rotational movement of said upper tilt bar like rotational movement will be imparted to the shutter blades and
- 10 the lower tilt bar, a cord secured at one end to said lower tilt bar and extending upwardly toward said upper tilt bar, first guide means on and adjacent the rotational axis of said upper tilt bar over which said cord passes, second guide
- 15 means on said upper tilt bar spaced radially from said rotational axis thereof, and from the first guide means, with which said cord is also engaged, and a fixed guide on said frame over which said cord passes after leaving said second guide
- 20 means.
2. A device of the class described comprising a frame bordering an opening, an upper tilt bar pivotedly mounted for rotational movement about its longitudinal axis on said frame adjacent one 25 side of said opening, a lower tilt bar likewise pivotedly mounted on said frame adjacent the opposite side of said opening, a plurality of shutter blades positioned in said opening between said tilt bars, means connecting said tilt bars and
- 30 said shutter blades together for supporting said shutter blades in spaced relation to each other and to said tilt bars and whereby upon rotational movement of said upper tilt bar like rotational movement will be imparted to the shutter blades
- 35 and the lower tilt bar, a pair of horizontally spaced parallel cords each secured at one end to said lower tilt bar and each extending upwardly toward said upper tilt bar, separate pairs of guide pulleys for each of said cords mounted
- on said upper tilt bar, one pulley of each pair around and over which said cords first pass being disposed closely adjacent the rotational axis of the upper tilt bar and the other pulley of each pair, around and below which said cords pass 5 after leaving said first-mentioned pulleys, being positioned respectively adjacent opposite longitudinal edges of said upper tilt bar, and separate fixed guide pulleys on said frame over which, respectively, the ends of said cords pass in converging relation.
3. A device of the class described comprising a frame bordering an opening, an upper tilt bar pivotedly mounted for rotational movement about its longitudinal axis on said frame adjacent one 15 side of said opening, a lower tilt bar likewise pivotedly mounted on said frame adjacent the opposite side of said opening, a plurality of shutter blades positioned in said opening between said tilt bars, means connecting said tilt bars and
- 20 said shutter blades together for supporting said shutter blades in spaced relationship to each other and to said tilt bars and whereby upon rotational movement of said upper tilt bar like 25 rotational movement will be imparted to the 30 shutter blades and the lower tilt bar, a cord secured at one end to said lower tilt bar and extending upwardly through the tilt bars and the shutter blades in coincidence with the respective rotational axes thereof, means carried by said 35 upper tilt bar for guiding said cord across said upper tilt bar from a position adjacent said rotational axis thereof to a position adjacent a longitudinal edge thereof, and guide means carried by said frame, and positioned in a plane coinciding with the respective rotational axes of said tilt bars and shutter blades, over which said cord passes.

CHARLES H. WOOD.
